DEMODULATOR FOR FREQUENCY AND AMPLITUDE MODULATION

Edward H. Lange, Baltimore, Md.

Application February 23, 1943, Serial No. 476,854

16 Claims. (Cl. 250—27)

This invention pertains to thermionic demodulator devices for converting the pattern of frequency-modulation of a high-frequency carrier-voltage into corresponding output voltages, and more particularly to apparatus for compensating undesirable modifications introduced or superposed upon these output voltages by extraneous amplitude-modulation of the carrier voltage, either at random, or by desired amplitude-modulated signal intelligence; and for utilizing the identical component parts and operating structure of the demodulator device, for also demodulating amplitude-modulation.

The principal object of this invention is to provide such a demodulator, having both high sensitivity of conversion, and economy of component parts, and to provide economy of space to accommodate these parts.

Another object of this invention is to provide such a demodulator capable of converting frequency deviations above and below a centre frequency into respective deviations of positive and negative voltages, directly proportional to the magnitude of the frequency deviations, without the necessity of regulating the impressed voltage upon the demodulator to a minimum determined by the weakest signal, to eliminate amplitude-modulation; also to provide operation of the frequency-demodulator from a variable norm of impressed voltage upon the demodulator, and to provide a selection of operating magnitudes of impressed voltage.

Another object of this invention is to provide in a frequency-demodulator, a useful unidirectional control-voltage, which varies in direct proportion to the amplitudes of the alternating currents supplied to the input-side of the demodulator, and which is independent of the frequency deviations from centre-frequency of these alternating currents, over the entire useful range of such frequency deviation.

A further object of this invention is to utilize this unidirectional control-voltage with suitable thermionic compensating means to provide a compensating voltage for a balanced modulator connected to the output-side of the frequency-demodulator, and of proper magnitude and phase relationship to compensate for the undesirable effect upon the output of the frequency-demodulator caused by variations in magnitude of the alternating currents supplied to the frequency-demodulator.

Still another object of this invention is to provide a demodulator, requiring no thermionic tube

or tubes ahead of the frequency-demodulator for amplitude-limitation, and providing selective amplification of either the frequency-demodulation or the amplitude-demodulation by the thermionic push-pull amplifier employed as part of the balanced modulator; also to provide simultaneous demodulation of both frequency-modulated signals and amplitude-modulated signals at the separate respective output terminals for these demodulations.

These objects, and others, are hereafter set forth in further detail in the following specification and appended claims, and will be better understood by reference to the drawing.

15 In the drawing,

Fig. 1 illustrates a demodulator in accordance with the principles of this invention, having a thermionic compensator tube, double-diode, resonant circuit and choke-coil connected to the double-diode, a thermionic push-pull amplifier, connections to the output circuit of the compensator tube from the push-pull amplifier, and selector means for selecting either frequency-demodulation or amplitude-demodulation for amplification by the push-pull amplifier; the resonant circuit and connected choke-coil being capacitively coupled with the impressed modulated alternating currents.

Fig. 2 illustrates another demodulator in accordance with the principles of this invention, having a thermionic compensator tube, double-diode, resonant circuit and choke-coil connected to the double-diode, and circuit connections from the output circuit of the compensator tube, for connection to the push-pull amplifier of Fig. 1; the resonant circuit being inductively coupled with the impressed modulated alternating currents, and the choke-coil being capacitively coupled with these currents.

Fig. 3 illustrates in diagram form, a mutual-conductance relationship with negative bias voltage upon the control-grid of the compensator tube, for providing the output voltage of the compensator tube utilized in the input circuit of the push-pull amplifier, to yield the necessary compensation for the undesirable effect of amplitude variations upon the output voltage of the frequency-demodulator.

Fig. 4 illustrates in vector-diagram form certain unique relationships found to exist with reference to voltage and current proportions, in the structures of Fig. 1 and Fig. 2, and employed to yield the important unidirectional control-voltage of this invention, independent of frequency

deviations from centre frequency, and for controlling the common control-grid voltage of a balanced modulator utilizing the push-pull amplifier.

Referring to Fig. 1 and Fig. 2, at 82 is a thermionic tube having anode 83, cathode 88, control-grid 81, and suppressor-grid 84 connected to the cathode 88 by conductor 89. Connected to the cathode 88 is the negative voltage bias-resistance 82', shunted by condenser 81. Terminals 90 and 91, connected respectively to control-grid 87 and bias-resistance 82', are input terminals for supplying modulated alternating voltages to the demodulators. At 72 is a source of unidirectional voltage, connected to ground 15 from the negative terminal of the source; positive voltage from the source is supplied to the screen-grid 86 by the variable conductor 92, and the anode 83 is connected to the positive terminal of the source 72, in Fig. 1, through the choke-coil 71, and in Fig. 2, through inductance coil 71. Connections to the tube 82, are illustrated only for the purpose of continuity, and for illustrating the utilization of a common source 72 of this invention, there being many well understood types of linkage with the principal terminals 70—85, Fig. 1, or 70a—85, Fig. 2, of this invention, and capable of supplying modulated alternating voltages to these terminals.

At 12 is shown a double-diode, having cathodes 14 and 26, and anodes 13 and 25. Shunted across the cathodes 14—26, are the equal resistances 27, 28, in series, the common junction b between these resistances being connected to ground 15 by conductor d. Condenser 29 is shunted across resistance 27, and condenser 30 is shunted across resistance 28. At 1 and 2 are equal resistances connected in series, and having the common connection or junction e, which is connected to ground 15 through the secondary coil 5 of the transformer 39—5. At 32 is a condenser connecting the cathode 14 with the terminal of resistance 1 opposite the junction e, and likewise at 31 is a condenser connecting cathode 26 with the terminal of resistance 2 opposite the junction e. At F₁ and F₂ are terminals connected respectively to the above-said terminals of resistance 2 and resistance 1, these terminals being output-voltage terminals for the alternating voltages developed by frequency-modulation impressed upon the demodulators.

At 7 is a thermionic compensator tube, having the cathode 96, anode 9, suppressor-grid 10 connected to cathode 96 by conductor 10a, control-grid 11, and screen-grid 8 connected to a positive voltage upon the source 72 by variable conductor 94, the control-grid 11 being connected by the variable contactor 36 to resistance 37. The anode 9 of tube 7, is connected to the source 72 through the primary winding 39 of transformer 39—5, by the variable conductor 93 connected to a positive voltage upon 72. The cathode 96 is connected by the variable contactor 74 to the bias-resistance 73, which is shunted across a part of the source 72, at the negative terminal of the source, and which has one terminal connected to the negative terminal of the source, at the ground 15. Shunted across the primary of the transformer 39—5, is the variable resistance 35, variable by contactor 35a.

Referring to Fig. 1, at 59—60, is a resonant circuit, having the coils 64, 63, and 58, and variable condenser 57. The choke-coil 56 has one terminal connected to the junction 60 between coils 63 and 58, and the other terminal connected

to the negative terminal 85 and ground 15 of source 72, through the condenser 75. The junction 59 between condenser 57 and coil 64, is connected to the terminal 70 of choke coil 71, through condenser 65. The junction 69 between coils 63 and 64, is connected by conductor 66 to the anode 13 of double-diode 12, and the junction 68 between condenser 57 and coil 58 is connected by conductor 67 to anode 25 of double-diode 12. Connected to the junction b between resistances 27 and 28, by conductor d, is a terminal of the resistance 37; the other terminal of resistance 37 being connected to the terminal 62 of choke-coil 56, which terminal is capacitively coupled with ground 15 through condenser 75. The resistance 37 carries the total unidirectional current of both diodes of the double-diode 12. Shunted across resistance 37 is the condenser 38; also shunted across resistance 37 is the condenser 40 in series with resistance 6, one terminal of resistance 6 being connected to ground 15 and conductor d, the other terminal being connected to terminal A₁. The terminals A₁ and ground 15 serve as output terminals for the alternating voltages developed by amplitude-modulation impressed upon the demodulator.

At 41 and 42 are thermionic tubes of a push-pull amplifier. Tube 41 has anode 44, suppressor-grid 45, control-grid 48, and screen-grid 49; likewise tube 42 has anode 43, suppressor-grid 52, control-grid 51, and screen-grid 53. Cathodes 46 and 47 of tubes 41 and 42 respectively, are each connected to the common junction 50 as are also the suppressor-grids 45 and 52, the junction 50 being connected by conductor 95a and variable conductor 95 to a positive voltage upon the source 72. Screen-grids 49 and 53 are connected by the common conductor 94a and the variable conductor 94 to a positive voltage upon the source 72. Shunted across the anodes 44 and 43 are the resistances 22 and 24 in series, the junction R between these resistances being connected by conductor 93a and variable conductor 93 to positive voltage upon the source 72. The resistances 17 and 18 are connected in series, the common junction h between these resistances being connected to ground 15; the opposite terminal 16 of resistance 17 is connected to anode 44 through condenser 21, and likewise the opposite terminal 19 of resistance 18 is connected to anode 43 through condenser 20. At 54 and 55 are switch-blades, each providing a two-position switching means. Blade 54 is connected to control-grid 48, and blade 55 is connected to control-grid 51. In position illustrated blade 54 connects with terminal F₂, and blade 55 with terminal F₁; in the alternative position blade 54 can be connected with A₂', and blade 55 with A₁, it being understood that the blades 54 and 55 are locked together in a manner well understood to move jointly. The resistances 22 and 24 are equal, likewise the resistances 17 and 18 are equal, and the tubes 41 and 42 are understood to have substantially identical characteristics.

The coils 63, 58, and 64, of the resonant circuit 59—60, are proportioned so that at exact resonance of this circuit to the centre frequency of the frequency-modulated alternating currents, the voltages between terminals 69 and 60 and between terminals 68 and 60, are equal. It will be understood that the resonant circuit 59—60, can be either of separate coils 63, 64, and 58, with condenser 57, or a single coil with condenser 57 connected to its terminals, the terminals 68, 60,

and 69 thereon being so placed as to provide the above stated equality of voltages.

In Fig. 2, the resonant circuit 63a—58a—51a, has the terminal 69a connected by conductor 66 to anode 13 of double-diode 12, and the terminal 68a connected by conductor 67 to anode 25 of double-diode 12. The terminal of resistance 37 opposite the ground-connected terminal of this resistance is connected to a terminal of the choke-coil 56a, the other terminal of choke-coil 56a being connected to the half-inductance point 60a upon the single inductance coil made up of the coils 63a and 58a in series. The variable condenser 57a is connected across the terminals 69a and 68a of the series-connected coils 63a and 58a. The variable condenser 76 is shunted across the inductance coil 77; the inductance coil 77 has mutual inductance with coils 63a and 58a, and the junction 60a upon these coils is capacitively coupled with the terminal 70a, by condenser 73. The terminals F₂ and F₁, and terminal A₁, are for use with the switching means 54—55 of Fig. 1, and with the push-pull amplifier connected to said switching means.

Having illustrated certain circuit connections embodying this invention, the principles of this invention are hereafter discussed to point out the important features, and with reference to the above-disclosed circuit connections.

In devices hitherto employed for demodulating frequency-modulated alternating currents, it has been necessary to eliminate any variations in amplitude of the impressed alternating currents, since such devices are also responsive to amplitude variations; without such elimination the resultant response to frequency-modulation would be distorted by extraneous voltages unrelated to frequency-modulation. Devices hitherto employed, and requiring one or more tubes to accomplish satisfactory elimination of amplitude variations, have employed a saturation principle, wherein alternating currents impressed in excess of a certain minimum value are unable to produce at the output side alternating currents larger than the minimum value. Such devices result in the employment of signals determined by the weakest signal-strength, and but little gain is contributed by the tube or tubes used to so limit the signal amplitudes. It is therefore necessary to provide, by means of the amplifying apparatus preceding such a limiting device, an excess of amplification such that the weakest signal will upon amplification, equal the constant norm fixed by the characteristics of the limiting device, and no benefit is thus derived from the signal-strengths which exceed such a fixed minimum. In the devices of this invention, operation of the demodulators takes place upon a selectable norm of input-signal amplitude, modifications of the amplitude of input signals above and below the norm being compensated in their effect upon the output voltages of the frequency-demodulator, by combining with these output voltages a compensating voltage. This combination is accomplished through the utilization of a balanced modulator, in which the compensating voltage is introduced as the common voltage upon both control-grids, and in which the compensating voltage is appropriately related to the changes in the ratio of the norm of alternating input currents to actual input alternating currents, and employed to cross-modulate the output voltages of the frequency-demodulator in such a manner as to cancel the undesired modifications of these output voltages

previously introduced by the modifications of amplitude of the input alternating currents.

In order to provide operation of the frequency-demodulator from a selectable norm of alternating current magnitudes, and provide the above-stated compensation, it is necessary to first produce a unidirectional control-voltage which is directly proportional to the amplitudes of the alternating currents impressed upon the demodulator, and which is at the same time, independent of the frequency deviations from centre-frequency, for the entire range of such deviations employed upon the demodulator. The discovery of means for utilizing such a control-voltage in a frequency-demodulator, to compensate for variations of alternating current amplitudes, by producing therefrom a cross-modulation factor inversely related to said amplitudes, and employing said factor in a balanced amplifier connected to said demodulator, is an important feature of this invention.

The principle of operation of the unidirectional control-voltage will be first pointed out with reference to Fig. 1, wherein a resonant circuit 59—60 is in series with a substantially pure inductive reactance of choke-coil 56. The stopping condensers 65 and 75 have negligible impedance at the operating carrier-frequencies, in relation to choke-coil 56 or to the resonant circuit 59—60. When the resistance 37 of the demodulators is short-circuited, there is present an uncompensated frequency-demodulator, operable upon a constant-amplitude frequency-modulated alternating current in the input circuit, 70—65—59—60—62—75—85, and capable of providing frequency-demodulation across the output circuit terminals F₂—15, and F₁—15. The conditions then existing, can be better understood by reference to Fig. 4. At 56e is shown vector representing the alternating voltage across the choke-coil 56; this vector is displaced in phase by 90 degrees from the alternating current through the choke-coil 56. The resonant circuit 59—60 is sharply resonant to the centre-frequency, the coils 63, 64, and 58 having a very high reactance-resistance ratio. Thus, at exact resonance for the centre-frequency, the alternating voltage across resonant circuit 59—60 is in phase with the alternating current passing through choke-coil 56, and is therefore 90 degrees displaced in phase from voltage 56e. At A is shown the vector voltage across the coil 63 of resonant circuit 59—60, and at B is shown the vector voltage across the coil 58 of the resonant circuit, at exact resonance to centre-frequency. When the voltage across coil 63 is directed toward terminal 60, the voltage across coil 58 is directed away from terminal 60. The voltage impressed across the anode-cathode 13—14 is determined by the resultant voltage across terminals 69—62, and likewise the voltage impressed across anode-cathode 25—26 is determined by the resultant voltage across terminals 68—62. At exact resonance, these resultant voltages are equal, and are shown by vectors E₁' and E₂'. The corresponding unidirectional currents through the diodes, are proportional to the magnitudes of these resultant voltages, and equal unidirectional currents flow from the cathodes through resistances 27 and 28 to the junction b, there being no resultant unidirectional voltage across resistances 27—28 in series, that is, between the cathodes 14 and 26. Condensers 29 and 30 have a negligible impedance in relation to resistances 27 or 28, at the carrier-frequency or centre-frequency. For a constant

alternating current through the choke-coil 56, the locus of the voltages across coils 58 and 63 is given respectively by the circles n' and n , as the frequency is deviated above and below the centre-frequency. For a small percentage change of the frequency from centre-frequency, the sharply resonant circuit 59-60 will have the voltage across coil 63 de-phased by 45 degrees; the voltage across coil 63 is then represented by the vector 63e, and likewise the voltage across coil 58 is then represented by the vector 58e. The resultant voltages across the diodes are now represented by voltage vectors E_1 and E_2 , and the currents flowing to the junction b are unbalanced, there being greater unidirectional current through resistance 27 than through resistance 28. For a frequency deviation on the opposite side of resonance or centre-frequency, this condition is reversed. There is thus produced across cathodes 14-26 a unidirectional voltage, which varies in direct proportion to frequency deviations from centre-frequency over a useful range, the voltage being zero at centre-frequency, and of opposite polarities for frequency deviations above and below centre-frequency.

It will be noted that the total unidirectional current, that is, the arithmetic sum of the unidirectional current of both diodes, flows through the conductor d, from junction b. This total current in general, varies with frequency deviations, and is therefore not inevitably an index of the magnitude of alternating currents flowing through the input circuit, 70-65-59-60-56-62-75-85; thus, even when the amplitude of the input alternating currents is constant, the total unidirectional current through conductor d will in general vary over a wide range with frequency deviations employed for frequency-modulation. An important feature of this invention is the means for obtaining independence of this total unidirectional current from frequency-deviations, over the entire useful range of such deviations in a frequency-demodulator, and for obtaining a unidirectional control-voltage therefrom, directly proportional to the amplitudes of the alternating current of the input circuit.

Thus, it will be seen from Fig. 4, that while the resultant voltage across cathodes 14-26 due to frequency deviations is determined by the arithmetic difference of voltages E_1 and E_2 , for any particular frequency deviation, that is, by the difference in unidirectional currents through the equal resistances 27, 28, the sum of these unidirectional currents is determined by the sum of the voltages E_1 and E_2 . The variation of this sum with frequency-deviation, can be illustrated from Fig. 4, in reference to a voltage ratio employed, that is, the ratio of alternating voltage across choke-coil 56 to alternating voltage across the resonant circuit 59-60, at the centre-frequency. Thus the vector A is a measure of the half-voltage across resonant circuit 59-60 when the junction 69 is at half-voltage across coils 63 and 64 in series. Comparison can then be readily made between the voltage sum E_1+E_2' for resonant frequency and the voltage sum E_1+E_2 for frequencies sufficiently deviated from resonance to de-phase by 45 degrees the voltages across coils 58 and 63; also as influenced by the ratio of voltage 56e to voltage A+B, that is, the ratio of voltage across choke-coil 56 to voltage across resonant circuit 59-60 at centre-frequency. Designating this latter ratio by N, then the percentage variation of E_1+E_2 from E_1+E_2' as related to N, is approximately as follows: When N is $\frac{1}{3}$,

variation is 29.5 per cent; when N is $\frac{1}{2}$, variation is 19.0 per cent; when N is 1, variation is 7.6 per cent; when N is 2, variation is 2.2 per cent; and when N is 3, the variation is 1.0 per cent. When the ratio N which is employed, is sufficiently large, the total unidirectional current can thus be made independent of the operating frequency-deviations upon the frequency-demodulator, to the extent required. When frequency-deviations are less than those sufficient to de-phase the resonant circuit voltages by 45 degrees, the percentage variations will be somewhat less, but since the frequency deviations must be a substantial percentage of this magnitude to yield adequate conversion voltages between cathodes 14 and 26, it is apparent that the ratio $N=1.0$, defines a minimum ratio, below which the total unidirectional current would be unsatisfactory for control purposes to compensate variations of input alternating current amplitude, or the effect of such variations upon the frequency-demodulator, because the unidirectional current cannot then be solely dependent upon the amplitudes of the input alternating currents.

In this invention, the resistance 37 is connected in series with the total unidirectional current from the diodes, to produce a unidirectional control-voltage, directly proportional to the amplitudes of the impressed alternating currents, and independent of frequency deviations over the entire range of such deviations employed upon the frequency-demodulator. This unidirectional voltage is impressed upon the control-grid 11 of tube 7, and produces a compensating voltage for the effect of amplitude-modulation upon the frequency-demodulator; this compensating voltage is developed across the terminals 3-4 of the secondary 5 of transformer 39-5, is designated herein as e_a , and discussed in further detail hereafter.

Referring to Fig. 1, when the switch-blades 54 and 55 are set to contact F₂ and F₁ respectively, the alternating voltage across resistances 1 and 2 in series set up by the differential voltage across the cathodes 14-26, is impressed upon the control-grids 48 and 51 of the push-pull amplifier. The cathodes 46, 47, are at a positive potential with reference to the ground 15, and the control-grids 48 and 51 thus have a constant negative bias-voltage introduced by way of circuit

50-95-15-4-5-3

for adjustment of the operating point with reference to the mutual conductance characteristic 55 of the tube 41 and 42. Tubes 41 and 42, are preferably selected to have a straight-line relationship between the mutual conductance and the negative bias-voltage, over a substantial operating range, that is with mutual conductance decreasing uniformly with increase of negative bias-voltage; such characteristics are present in numerous conventional pentodes. If the mutual conductance is designated by g_m for the pentodes 41 and 42, then the rate of change of mutual conductance g_m with negative bias-voltage is constant in the operating range employed, and higher derivatives of mutual conductance g_m with negative bias-voltage are zero, over the operating range.

From a quantitative consideration of the voltage difference E_1-E_2 , e. g. from Fig. 4, as related to the frequency-deviation from centre-frequency, designated by Δf , to the amplitude of the alternating current through the choke-coil 56 connected to the diode-connected resonant circuit,

designated by I_a , and to composite circuit constants of the demodulator network, designated by K , the conversion-voltage across cathodes 14-26 is readily shown to be

$$E_f = K I_a \Delta f \quad (1)$$

The impedance of condensers 32 and 31, is negligible for the low or demodulated frequencies, in relation to resistances 1, or 2, and the conversion-voltage across the resistances 1 and 2 in series is thus substantially identical with the voltage across diode-cathodes 14-26. It will be evident that the alternating component of voltage across diode-cathodes 14-26 can be alternatively applied to the terminals F_2 -3- F_1 of the push-pull amplifier by transformer coupling, the primary being coupled with the diode-cathodes 14-26, and the secondary having terminals connected respectively with terminals F_1 and F_2 , and a centre-tap connected to terminal 3, in a manner well understood.

The total alternating voltage across resistances 1 and 2, is thus E_f , half of this voltage being across resistance 1, and half across resistance 2, these voltages being in the same direction, so that when this voltage produces a positive polarity on one control-grid, it produces a negative polarity on the other control-grid, and vice versa. The compensating voltage e_a introduced at the terminals 3-4, is common to both control-grids 48 and 51, and produces the same polarity on both control-grids. With reference to the resultant voltage applied to each of the control-grids 48 and 51, it is evident that the sum of voltage e_a and voltage $E_f/2$ is applied to one of these grids and the voltage difference $e_a - E_f/2$ is applied to the other grid. The resultant voltage developed across the terminal $s-t$ of the resistance 22-24 in series, is thus determined by the difference of the anode currents through resistances 22 and 24, and the magnitude of the equal resistances 22 or 24. Condensers 21 and 20 have negligible impedance for the low or demodulated frequencies, in relation to resistances 17 or 18, and the output voltage of the amplifier at terminals 16-19 is substantially the same as the voltage across $s-t$, the continuous component of current being absent from resistances 17 and 18. In accordance with the well known relation in such a balanced modulator, the variation current through one of the anodes is

$$a_1(e_a + E_f/2) + a_2(e_a - E_f/2)^2$$

and through the other anode

$$a_1(e_a - E_f/2) + a_2(e_a + E_f/2)^2$$

The difference of these anode variation currents is:

$$a_1 E_f \left(1 + 2 \frac{a_2}{a_1} e_a \right) \quad (2)$$

wherein the coefficients a_1 and a_2 are respectively proportional to the mutual conductance g_m , tube and circuit constants, and to the rate of change of g_m with negative bias-voltage, tube and circuit constants.

It will be noted that the resultant output-voltage across terminals 16-19 differs from the output-voltage E_f across terminals F_1 and F_2 , by the cross-modulation factor determined by the compensating voltage e_a , as indicated in Equation 2. As indicated by Equation 1, the output-voltage of the frequency-demodulator at terminals F_1 and F_2 depends upon both the amplitude of alternating input currents I_a , and upon the fre-

quency deviation Δf . The resultant output-voltage across terminals 16-19, in view of Equations 1 and 2 is therefore:

$$K' \Delta f I_a (1 + k e_a) \quad (3)$$

in which K' is a constant which takes into account constant K , and also constant a_1 and the resistance of 22, and constant k takes into account the ratio a_2/a_1 . Thus for proper compensation of the effect of changing amplitudes of alternating input current, I_a , it is evident that when I_a is equal to the norm selected, designated by I_{ao} , the compensating voltage e_a must be zero; also when I_a increases above the norm e_a must be negative, and when I_a decreases below the norm e_a must be positive; and further, that the magnitude of changes of e_a in relation to I_a must be such as to maintain the product $I_a(1 + k e_a)$ constant, and equal to the selected norm I_{ao} .

The provision of such a compensating voltage is an important feature of this invention. The nature of the required variation of the compensating voltage is indicated by the necessary equality:

$$I_a (1 + k e_a) = I_{ao} \quad (4)$$

or

$$e_a = \frac{1}{k} (I_{ao}/I_a - 1) \quad (3)$$

The cathode 96 of compensator tube 7, can be set at a voltage which is positive with reference to the ground 15, by means of the adjustable contactor 14 upon the resistance 73. The circuit from cathode to control-grid 11, is 96-74-13-15-37-36-11; it will be noted that the total unidirectional current of both diodes flows through resistance 37, in the direction from conductor d to the connected choke-coil, 56, or 56a, and that the control-grid is placed at a further negative voltage by the flow of total unidirectional current through resistance 37, from conductor d to contactor 36, in addition to any negative bias-voltage from 74-13.

When the proportioning of the voltages upon the resonant circuit and conductively-connected choke-coil has been brought within the limits previously discussed, with reference to the ratio N previously defined, then the total unidirectional current through resistance 37 is directly proportional to the alternating current amplitudes I_a , of the demodulator networks, and independent of the magnitudes Δf of frequency deviations employed; an increase of current I_a above any norm I_{ao} selected, then produces a proportionate increase of negative bias-voltage upon control-grid 11, and likewise a decrease of current I_a below current norm I_{ao} produces a proportionate decrease of negative bias-voltage, below that of the norm. Corresponding current variations are set up in the anode circuit 9-35a-35-93-12-14-96. The variable resistance 35, serves to regulate the voltage impressed upon the primary of the transformer 39-5; the resistance 35 can be made small in relation to the anode-cathode resistance of the pentode 1, and in relation to the reactances of the primary 39, over the range of frequencies for which compensation of variations of alternating current amplitude is desired, and the compensating voltage e_a of the secondary 5 made to vary in response to current I_a , that is with the total unidirectional current through resistance 37. Reference to the necessary equality which must be maintained, Equa-

tion 3, indicates the nature of mutual-conductance characteristics required to accomplish this equality, for purposes of compensation, as disclosed. Referring to Fig. 3, at 99 is indicated a graph of mutual-conductance of compensator tube 7 in relation to the origin O, the magnitudes of mutual-conductance G_m being indicated along the axis of ordinates; the abscissas indicating the magnitudes of negative bias-voltage E_g upon the control-grid 11, produced by the unidirectional total diode current flowing through resistance 37, and with reference to the origin O', the distance between O and O' indicating any permanent negative bias-voltage introduced by 74-73. At E_{go} is indicated a norm of negative bias-voltage selected for a particular input alternating current norm I_{ao} . With reference to the origin O', the ratio of any negative bias-voltage E_g to any norm of negative bias-voltage E_{go} , is the same as the ratio of the respective alternating currents, i. e. $I_{ao}/I_a = E_{go}/E_g$, and as previously noted, the compensating voltage e_a is directly proportional to the variation of current through anode 9. Thus the equality indicated by Equation 3 yields the tube characteristic required, in the form:

$$i_p = \frac{1}{k'} (E_{go}/E_g - 1) \quad (4)$$

in which i_p is the magnitude of the variation-current through the anode 9, and k' takes into account the constant k , as well as the constant proportionality of e_a with the anode variation-current, the variation-current being the difference between any current to the anode 9 and the current to the anode 9 when the negative-bias voltage is at the norm E_{go} . The mutual-conductance characteristic best suitable for such control, follows from the definition of this quantity, which is well known, and indicates that mutual conductance G_m should vary as the inverse square of the negative bias-voltage upon control-grid 11, or approximately in this manner. Such a characteristic is obtainable in numerous conventional pentodes, referred to as super-control tubes, or variable-mu tubes, and grid bias in addition to that afforded by resistance 37 for control purposes, is provided to better attain these objects.

It will be understood that the quantitative relations pointed out herein, are intended to aid in the better understanding of the principles of this invention, and are not to be understood as any manner of limitation upon the structures disclosed herein.

It should be noted that Equation 1 is for conventional types of frequency-demodulating circuits, and that the amplitude of the received alternating currents is involved as a factor, determining the frequency-demodulated voltage E_f . It will thus be evident, for example, that the simple superposition of modifying voltages upon E_f through the use of a single thermionic tube in which both E_f and the modifying voltages are applied to grid means of the tube, cannot annul the undesired modifications of E_f for any appreciable range of amplitude modulations, in the sense of actually compensating for such magnitudes of random variations, by means of such modifying voltages varying in a direct proportion to alternating current amplitudes; the receiving apparatus has no control whatsoever over the extent of such amplitude-modulation. Further, the mere superposition of modifications simply be-

cause they are in a direct proportion to amplitude variations will equally well result in over-modifications of the same order of magnitude as the original undesired arbitrary modifications, for any appreciable range of amplitude variations. The corrective processes called for, require a multiplying factor; processes of direct addition or deduction as above noted, lead to the undesired results stated. The present invention is not concerned with such arbitrary counter-modifications of the amplitude-modulation, which necessarily over-modify for a very substantial and useful range of amplitude-modulation, over which the device has no control, resulting in undesired modifications comparable with no corrective processes at all. Such processes do not constitute compensation within the objects of this invention. The above-noted defects are also present when voltages of like polarity are utilized upon grid control means in each tube of a two-tube push-pull amplifier, when such voltages are modified in a direct proportional relation to amplitude variations of the received alternating currents. With further reference to arbitrary counter-modifications, it is evident to anyone skilled in the art that since undesired modifications of E_f occur in relation to alternating current amplitudes as the cause, counter-modifications if employed at all, must necessarily be in relation to these alternating current amplitudes; likewise the superposition of arbitrary magnitudes of counter-modifications through grid control means of thermionic tubes, is well understood in the art. It is also well known by those skilled in the art of physical applications, that however intricate a functional relation may be, it can be matched over a sufficiently infinitesimal range by a simple additive or subtractive variation. However, the range of random amplitude variations and corresponding undesirable variations of E_f is not under control of the receiving apparatus, being externally determined, and consequently such a highly restricted range as above-noted is of little practical value, especially since a wide range of random undesired modifications can then produce over-modifications of the voltage E_f comparable with the undesired modifications existing with no corrective apparatus. An important feature of the present invention is the means providing a cross-modulating factor which varies inversely with the amplitudes of received alternating currents, making possible the actual compensation of random amplitude variations over a wide range, and the simultaneous utilization of both amplitude-demodulation voltages and frequency-demodulation voltages.

When the switch-blades 54, 55, are switched to contacts or terminals A₂' and A₁ respectively, the compensating voltage e_a is eliminated, the output-voltage across resistance 6 due to amplitude-modulation being applied across control-grid 51 and cathode 47. Terminal A₂' is connected by variable connector 23, to the output-resistance 18, for phase-inversion, to apply to control-grid 48 an equal voltage of opposite phase to that applied to control-grid 51, by the resistance 6.

It will be noted that when switch-blades 54 and 55 are connected respectively to terminals F₂ and F₁, frequency-demodulation compensated for the effect thereon of amplitude-modulation, is available at the terminals 16-19, and that simultaneously, amplitude-modulation is available at terminals A₁-15, and can be taken from these terminals directly or by another amplifier.

The above-disclosed demodulators thus provide simultaneous reception of both the amplitude-modulation and the frequency-modulation from an impressed carrier-voltage having both of these modulations; also these demodulators afford a useful control of devices interconnected between the output-terminals for frequency-modulation and the output-terminals for amplitude-modulation, through the medium of phase-control, or amplitude-control, or both, with reference to the low or modulation-frequency impressed upon the carrier, that is, upon both the amplitudes and upon the centre-frequency. For example, if a low frequency f_L is impressed upon the carrier so as to modulate both the amplitudes of the carrier and the centre-frequency of the carrier, a selective control is provided by the above-disclosed demodulators and for devices interconnected between output-terminals, by control of the phase-shift of the modulating-voltage of frequency f_L upon the amplitude-modulator in relation to the modulating-voltage of frequency f_L upon the frequency-modulator. In reference to the T-connection formed by terminals 16—19—A₁, and when the terminals F₁ and F₂ are respectively in contact with switch-blades 55 and 54, it will be noted that when these modulating-voltages are in phase, and the demodulator output-voltages are adjusted to equality, for example by taking the terminal A₁ from an intermediate position upon resistance 6, or by taking the terminals 16, 19, from equal intermediate positions along resistances 17 and 18, respectively, in a manner well understood, then zero voltage is established between a pair of interconnected terminals, such as A₁—16, and double voltage is established between terminals A₁—19. When the same modulating-voltages are shifted to exact phase-opposition, then zero voltage is produced across terminals A₁—19, and double voltage across terminals A₁—16. When the phase shift between the modulating-voltages is varied, and has values between the in-phase and phase-opposition positions, various degrees of output-voltage magnitudes across these output-voltage terminals are produced, and controlled by the controlled composition of the carrier-voltage, as to the phase-shift. There is thus provided, these additional means for the control of devices connected to the output-terminals of the demodulators, and for the reception of signal-intelligence. As a further example, it will be noted that if the output-voltage from terminals A₁—15, or from another amplifier connected to this voltage, such as is illustrated for the connections A₁, A₁', is proportioned to 86.6 percent of the output-voltage across 16—19, and the phase-shift is 90 degrees, then in addition to the production of device-operating voltages across terminals 16—19, and 15—A₁ or the amplifier output-equivalent of terminals 15—A₁, there is produced a three-phase system with reference to the terminals 16, 19, and A₁. As is well known, such a three-phase system can be readily employed for the production of a rotating electric or magnetic field for control purposes, it being evident that the direction of rotation is controllable by the particular 90 degree phase displacement chosen, and the speed of rotation by the frequency f_L which is employed.

In the Figures 1 and 2, condenser 40 has a negligible impedance at the low or demodulated frequencies, in relation to resistance 6; also condensers 29, 30, and 38, are intended to by-pass the high or carrier-frequencies around the respective resistances across which they are shunted,

and thus have negligible impedance at these frequencies in relation to the respective resistances which are shunted. Condenser 73, Fig. 2, has negligible impedance at the carrier-frequencies, in relation to the impedance of the choke-coil 56a, so that substantially the full input alternating voltage across terminals 70a—85, is impressed across choke-coil 56a.

Having thus described several illustrative embodiments of my invention, it will be evident that changes can be made in the form and arrangement of parts without departing from the spirit of my invention, as set forth in the appended claims, and I do not therefore limit the scope of the invention to such particular embodiments, or otherwise than by the terms of the appended claims.

What is claimed is:

1. A demodulator providing separate frequency-demodulation output-voltages and amplitude-demodulation output-voltages, simultaneously, from an impressed high-frequency carrier-voltage, said demodulator having a thermionic double-diode, a resonant circuit, connections between said double-diode and resonant circuit including a first resistance connected between the cathodes of said double-diode, a connection from each anode of said double-diode to said resonant circuit, and a second resistance connected from the half-resistance point upon said first resistance to said resonant circuit; a ground connection at said half-resistance point, and thermionic tube compensating means having a control-grid to cathode control-circuit including connections between said second resistance and ground connection, compensating the effect of amplitude variation upon said frequency-demodulation output-voltages.

2. The combination with a demodulator for demodulating constant-amplitude frequency-modulated alternating currents, of a compensator device, said demodulator having a double-diode, a first resistance connected between the cathodes of said double-diode, a resonant circuit having an inductance coil, a conductive connection between the anodes of said double-diode including inductance of said coil, and a choke-coil connected from the half-resistance point upon said first resistance to the half-inductance point upon said included inductance between said anodes, said compensator device having a second resistance connected in series with said choke-coil, between said half-resistance point and said choke-coil, a thermionic compensator tube having a cathode, anode, and control-grid, a ground connection at said half-resistance point, connections between the compensator tube control-grid and compensator tube cathode including said ground connection and a part of said second resistance, and a balanced modulator including a thermionic push-pull amplifier having a first control-grid and a second control-grid, an impedance between said first and second control-grids coupled with said first resistance, and coupling means coupling the half-impedance point of said impedance with the compensator tube anode-cathode.

3. A demodulator for demodulating frequency-modulated and amplitude-modulated alternating currents, said demodulator having a double-diode, a first resistance connected between the cathodes of said double-diode, a resonant circuit having an inductance coil, a conductive connection between the anodes of said double-diode including inductance of said coil, and a choke-coil connected in series with a second resistance, one ter-

75 minal of said choke-coil being connected to the half-inductance point upon said included inductance between said anodes, and one terminal of said second resistance being connected to the half-resistance point upon said first resistance and to the ground, a thermionic compensator tube having a cathode, anode, and control-grid, connections between the compensator tube control-grid and cathode including said ground connection and a part of said second resistance, and a balanced modulator including a thermionic push-pull amplifier having a first and second control-grid, an impedance connected between said first and second control-grids coupled with said first resistance, and coupling means coupling the half-impedance point upon said impedance with the compensator tube anode-cathode.

4. The combination with the structure of claim 3, of selector means, including a two-position switch connected to said first and second control-grids, one of said positions connecting these control-grids to said impedance, the other of said positions connecting the first control-grid to a third resistance shunted across said second resistance through a condenser, and connecting the second control-grid to a phase-inverting connection upon said push-pull amplifier.

5. In a carrier-wave receiving system for simultaneously employing frequency-modulation and amplitude-modulation, a demodulator device for simultaneously demodulating frequency-modulated voltages and amplitude-modulated voltages, and for combining said voltages, said device having a resonant circuit, diode rectifying means conductively connected to said resonant circuit, a two-tube push-pull thermionic amplifier having an output-impedance for frequency-demodulated voltages, an input-impedance connected with grid means in each of said tubes, and a first coupling means coupling said input-impedance with said diode means, impressing alternating voltages of opposite polarity upon said grid means, an output-impedance for amplitude-demodulated voltages, a second coupling means coupling said output-impedance for amplitude-demodulated voltages with said diode means, a third coupling means including a grid-controlled thermionic conductance, coupling the half-impedance point upon said input-impedance with said diode means, impressing compensating voltages of like polarity upon said grid means in a reciprocal relationship to the magnitudes of said amplitude-modulated voltages, and a common connection between said output-impedances, whereby said output-voltages are serially combined.

6. In a frequency-demodulator, a double-diode, a first resistance connected between the cathodes of said double-diode, a resonant circuit having an inductance coil, a conductive connection between the anodes of said double-diode including inductance of said coil, a connection from the half-inductance point upon said included inductance between said anodes to the half-resistance point upon said first resistance including a choke-coil and a second resistance in series, said second resistance having one terminal connected to said half-resistance point, coupling means coupling said resonant circuit and said choke-coil with a source of modulated alternating voltages, and a ground connection at said half-resistance point upon said first resistance.

7. In combination with the structure of claim 6, thermionic control-means, including a cathode and a control-grid, and circuit connections between said cathode and control-grid of said ther-

75 mionic control-means including said ground connection and said second resistance.

8. In combination with the structure of claim 6, a balanced-modulator including a resistance-coupled push-pull amplifier having a first control-grid and a second control-grid, a first coupling means coupling said second resistance with said first and second control-grids, and a second coupling means coupling said first and second control-grids with said first resistance.

9. In combination with the structure of claim 6, a balanced-modulator including a resistance-coupled push-pull amplifier having a first control-grid and a second control-grid, a first coupling means coupling said second resistance with said first and second control-grids, a second coupling means coupling said first and second control-grids with said first resistance, and a third coupling means coupling a third resistance with said ground connection and with said second resistance, whereby frequency-demodulation is provided across the output circuit of said push-pull amplifier, independent of amplitude-modulation of said modulated voltages, and whereby demodulation of said amplitude-modulation is simultaneously provided across said third resistance, independent of the frequency-modulation of said modulated voltages.

10. A demodulator device, said device having a double-diode, a first resistance connected between the cathodes of said double-diode, a resonant circuit having an inductance coil, a conductive connection between the anodes of said double-diode including inductance of said coil, a connection from the half-inductance point upon said included inductance between said anodes to the half-resistance point upon said first resistance, including a choke-coil and a second resistance in series, said second resistance having one terminal connected to said half-resistance point, a ground connection at said half-resistance point upon said first resistance, coupling means coupling said resonant circuit and said choke-coil with a source of modulated alternating voltages, and a balanced-modulator including a resistance-coupled push-pull amplifier having a first control-grid and a second control-grid, a second coupling means coupling said second resistance with said first and second control-grids, and a third coupling means coupling said first and second control-grids with said first resistance.

11. In combination with the structure of claim 10, a fourth coupling means, coupling a third resistance with said ground connection and with said second resistance, and selector means selectively connecting said first and second control-grids respectively with said third resistance, and with a phase-inverting connection upon an output-resistance of said amplifier.

12. In a frequency-demodulator for demodulating frequency-modulated alternating currents, the device for stabilizing the factor of alternating current magnitudes in the conversion ratio of frequency-deviation to output-voltage, independent of random variations of amplitudes of said alternating currents, said demodulator having a resonant circuit, and diode voltage rectifying means including a resistance coupled with said resonant circuit, providing unidirectional voltages upon said resistance in a direct proportion to amplitudes of said alternating currents and substantially independent of frequency-modulation, said device including a two-tube push-pull amplifier, each tube having a cathode, anode, and grid control means for controlling cathode-anode currents

therein, said amplifier having an output-impedance for frequency-demodulated voltages coupled with said anodes, an input-impedance connected between said grid control means coupled with said diode means, and a thermionic compensator tube with anode, cathode and a grid, having a first coupling means coupling said compensator tube grid and compensator tube cathode with said resistance, and a connection between said input-impedance and said cathodes of said amplifier, including a second coupling means coupling said grid control means with said compensator tube cathode-anode, impressing voltages of like polarity upon said grid control means and providing a compensating cross-modulating factor varying in inverse relation to the amplitudes of said alternating currents.

13. The combination with a frequency-demodulator for demodulating frequency-modulated carrier currents, said demodulator having the capability of providing output-voltages directly proportional to frequency deviations from a centre frequency, and directly proportional to the amplitudes of said carrier currents, of a compensator device for compensating the undesired effects of amplitude variations of said carrier currents upon said output-voltage, said device having a two-tube thermionic push-pull amplifier for amplifying said output-voltages, and compensator means for controlling a cross-modulating factor of said push-pull amplifier, including a thermionic compensator tube with cathode, grid, and anode, a first coupling means coupling said compensator tube grid-cathode with said demodulator, and a second coupling means coupling said compensator tube cathode-anode with grid controlling means in each of said tubes of said push-pull amplifier.

14. A frequency-demodulating device for demodulating frequency-modulated carrier currents, said device having a resonant circuit, diode voltage rectifying means including a resistance coupled with said resonant circuit, and a two-tube push-pull thermionic amplifier, each tube having a cathode, anode, and grid control means for controlling the cathode-anode thermionic currents therein, said amplifier having an output impedance for frequency-demodulated voltages connected between said anodes, an input-impedance connected between said grid control means and coupled with said diode means, a thermionic compensator tube with anode, cathode and grid, a second coupling means coupling said compensator tube grid and compensator tube cathode with said resistance, and a common connection between said grid control means and said cathodes of each of said two amplifier tubes including a third coupling means, coupling said grid control means with said compensator tube cathode-anode.

15. In a frequency-modulation receiver having a frequency-demodulator with a resonant circuit and diode voltage rectifying means including resistance connected with said resonant circuit, and a two-tube thermionic push-pull amplifier for providing a substantially constant voltage amplification-ratio, each tube having a cathode, anode, and grid control means for controlling thermionic currents therein, said amplifier having an input-impedance connected between said grid control means, an output-impedance connected between said anodes, and a coupling means coupling said input-impedance with said rectifying means, a compensator device for compensating undesirable modifications of said frequency-demodulated voltages caused by amplitude variations in the impressed carrier wave, said compensator device including a thermionic compensator tube with compensator tube cathode, compensator tube anode, and compensator tube grid, a circuit connection between said compensator tube grid and compensator tube cathode including a coupling with said resistance, and a common circuit connection between said grid control means and said cathodes of said two amplifier tubes, including a coupling with said compensator tube anode and compensator tube cathode.

16. A frequency-demodulator having a resonant circuit, and a two-tube thermionic push-pull amplifier for providing a substantially constant voltage-amplification ratio, each tube having a cathode, an anode, and grid control means for controlling thermionic currents therein, said amplifier having an output-impedance for frequency-demodulated voltages connected between said anodes, an input-impedance connected between said grid control means, coupling means including resistance coupling said input-impedance with said resonant circuit and impressing voltages of opposite polarity upon said grid control means, and a compensator means for impressing compensating voltages of like polarity upon said grid control means and regulating the magnitudes of said compensating voltages, including a thermionic compensator tube with compensator tube cathode, compensator tube anode, and compensator tube grid control means, a common circuit between said amplifier tube grid control means and said amplifier tube cathodes including a coupling with said compensator tube cathode and compensator tube anode, and means for impressing voltages upon said compensator tube grid control means including a connection between compensator tube grid control means and said resistance.

EDWARD H. LANGE.
